CLAIM

The ornamental design for a display screen with icon as shown and described.

DESCRIPTION

This patent or application file contains at least one drawing executed in color. Copies of this patent or patent application with color drawing(s) will be provided by the Office upon request and payment of the necessary fee.

FIG. 1 is a display screen or portion of a display screen with icon according to a first embodiment;

FIG. 2 is a display screen or portion of a display screen with icon according to a second embodiment;

FIG. 3 is a display screen or portion of a display screen with icon according to a third embodiment;

FIG. 4 is a display screen or portion of a display screen with icon according to a fourth embodiment;

FIG. 5 is a display screen or portion of a display screen with icon according to a fifth embodiment; and,

FIG. 6 is a display screen or portion of a display screen with icon according to a sixth embodiment.

The broken lines in the drawings illustrate portions of the icon and form no part of the claimed design.

(Continued)

Discusses sensitive information →

The perimeters of the portion of the underlying portion of a display screen and the icon are understood to be flush.
